UNITED STATES PATENT OFFICE

ERNEST V. HARKNESS, OF DECATUR, ILLINOIS

ICE TONGS

Application filed January 18, 1929. Serial No. 333,430.

This invention relates to improved ice tongs and has special reference to a structure of this kind which is characterized by a new principle of leverage and a carrying handle structure.

My principal aim is to generally improve upon structures of this class by providing one which is mechanically different from known tongs, and such in construction that it is economical, practicable, unusually efficient in performance, positive and dependable as well as quick in action, and capable of better fulfilling the requirements of an implement of this kind.

Other features and advantages of the invention will become more readily apparent as the description proceeds.

In the drawings:

Figure 1 is a side elevational view of a pair of tongs constructed in accordance with the present invention.

Figure 2 is an edge elevation of the same.

Figure 3 is a cross sectional view, taken approximately upon the plane of the line 3—3 of Figure 1.

In the drawings, the reference characters 4 and 5 designate a pair of duplicate levers, whose intermediate portions are disposed in intersecting relation and pivotally connected to each other as at 6. It is to be observed that the pivot of this particular arrangement is between the center and upper end of the levers, thus providing a comparatively short upper handle portion 7, and relatively long

jaw portions 8. The jaw portions 8 terminate in inwardly directed gripping claws 9. This provides an unusually dependable type of leverage, insuring a firm grip on the objects and quick engagement and releasing. It is

to be noted that the upper end portions 7 terminate in integral eyes 10. Fastened to each eye is a ring 11, and fastened to the ring is a link including an eye portion 12 directly connected with the ring 11 and an eye portion 13 arranged at right angles and connected with a retaining hook 14, on one end of the handle 15. This handle includes a hand grip portion 16 of channel shaped cross section as shown in Figure 3, to render it comfortable and easy to handle. In fact, the entire

handle 15 is formed of a piece of metal whose central portion is of channel shaped cross section, and whose end portions are reduced in proportion and bent to form the hooks 14 which fasten through the link.

The structure is of course duplicated at each end.

The first advantage of the ice tong is the size and shape. This is brought about by the fact that the distance from the fulcrum to the pointed claws of the tongue where the load is carried is less than in ordinary ice tongs. The second advantage is that the eye where the handle fastens to the tong are forged solid and bent as is the ordinary case, and are therefore more rigid. The link and ring connections between the hand grip also constitutes an important structural distinction in the complete structure. The tongs are unusually light in weight and the claws are such that they will easily take hold of an object at any angle and will release instantly. The chain handle will seldom ever tangle or kink and will stand almost any amount of hard usage and strain.

These and other advantages and features have doubtless been made apparent from the foregoing description and the drawings, and consequently a more lengthy description is regarded as unnecessary.

Minor changes in the shape, size, materials, and rearrangement of details coming within the field of invention claimed may be resorted to in actual practice, if desired.

I claim:

A pair of ice tongs comprising a pair of crossed pivotally connected levers including handle portions and jaw portions, the pivotal connection being disposed between the centers and upper ends of said levers whereby to provide relatively short upper portions and comparatively long lower portions, and a carrying handle connected with the upper extremities of the said handle portion, said carrying handle comprising a longitudinally bowed channel shaped hand grip terminating at its opposite end in connecting hooks, and flexible connectors between the hooks and upper ends of said levers, said flexible connectors each including a ring connected with the comple-

mental lever, and a double-eyed link connected with the ring and with the adjacent hand grip hooks, the eyes of said hook being turned at right angles with respect to each other.

5 In testimony whereof I affix my signature.

ERNEST V. HARKNESS.
